US0D1025995S

(12) **United States Design Patent** (10) **Patent No.:** **US D1,025,995 S**
(45) **Date of Patent:** **** May 7, 2024**

(54) **SUPPORT FOR ELECTRIC DEVICES**

(71) Applicant: **Jiajia He**, Liuzhou (CN)

(72) Inventor: **Jiajia He**, Liuzhou (CN)

(**) Term: **15 Years**

(21) Appl. No.: **29/820,867**

(22) Filed: **Dec. 24, 2021**

(30) **Foreign Application Priority Data**

Jun. 24, 2021 (CN) 202130395516.1
